UNITED STATES PATENT OFFICE.

JESSE G. VINCENT, OF DETROIT, MICHIGAN, ASSIGNOR TO PACKARD MOTOR CAR COMPANY, OF DETROIT, MICHIGAN, A CORPORATION OF MICHIGAN.

HYDROCARBON MOTOR.

Application filed September 28, 1921. Serial No. 503,876.

To all whom it may concern:

Be it known that I, JESSE G. VINCENT, a citizen of the United States, and resident of Detroit, Wayne County, State of Michigan, have invented certain new and useful Improvements in Hydrocarbon Motors, of which the following is a specification.

This invention relates to hydrocarbon motors and particularly to the construction and arrangement of the intake conduit and the heating jackets therefor.

One of the objects of the invention is to provide a motor intake pipe or conduit with jacketing means that will insure heating all parts of the pipe.

Another object of the invention is to provide a sectional intake pipe with interconnected water jackets so that all of the sections of the pipe may be heated.

Other objects of the invention will appear from the following description taken in connection with the drawings, which form a part of this specification, and in which—

Fig. 1 is a plan view of a hydrocarbon motor embodying the invention;

Fig. 2 is a part sectional and part elevation of the motor shown in Fig. 1;

Fig. 3 is an enlarged section on the line 3—3 of Fig. 2;

Fig. 4 is an enlarged section on the line 4—4 of Fig. 2; and

Fig. 5 is an enlarged section on the line 5—5 of Fig. 1 and on both of the lines 5—5 of Fig. 2.

Referring to the drawings 10 represents the cylinders of a hydrocarbon motor. The motor illustrated is a six-cylinder motor though parts of only five cylinders are shown in the drawings, the other parts being broken away.

Each of the cylinders is water jacketed and an outlet pipe is shown at 11, this pipe being near the top of the cylinder. Each of the cylinders is also formed with a pair 45 of inlet elbows 12 in which the inlet ports are formed. The exhaust elbows and ports are on the other side of the cylinders and are not shown in the drawings. All of these elbows and ports are also arranged at the 50 top of the cylinders.

The inlet ports of the cylinders are fed by an inlet conduit or pipe which is shown as formed in three separate sections, two upper sections 13 and a lower section 14 to 55 which the carburetor 15 is connected. Each

of the sections 13 is formed with short pipe extensions 16 which are connected to the elbows 12 above described. Each of the sections is also formed with a water jacket space 17 preferably on two walls of the 60 conduit as shown particularly in Figs. 3 and 5. Short pipe extensions 18 from the jacket 17 connect with the outlet pipes 11 from the cylinders so that all of the water from the jackets of the cylinders enters these 65 jackets 17 of the conduit sections 13.

One of the sections 13 is provided with a water outlet 19 from the jacket 17 and this outlet is adapted to be connected to a radiator or other suitable means for cooling the water. From the radiator the water is, of course, pumped back to the motor cylinders in the usual way so that a complete circulation is maintained.

The intake conduit section 14 is also provided with a water jacket, indicated at 20, this also being on two walls as shown in Fig. 4, and the section is detachably connected to the sections 13 as by the bolts 21. Thus the carburetor 15 connects through the 80 main passage of the section 14 with the main passages of the two sections 13 and from the latter sections the combustible mixture passes to the motor cylinders.

Each of the jackets 17 of the conduit sections 13 is in communication with the jacket 20 of the section 14, this connecting passage 22 being shown particularly well in Fig. 5, said Fig. 5 being a section on both of the lines 5—5 of Fig. 2. It is also shown in Fig. 90 1 where one of the sections 13 is cut away in the lower left-hand corner of the figure.

It will be seen that with an outlet to the radiator from only one of the sections 13 all of the water flowing from the three cylinders into the jacket of the left-hand section 13 must of necessity flow through the communicating passage 22, the jacket 20 and then through the communicating passage 22 to the jacket of the right-hand section 13. This is 95 leaving out of consideration for the moment a secondary passage between the two sections 13 which will be hereinafter referred to. Thus the section 14, even though it is much lower down than the inlets to the sections 13, will receive sufficient hot water to thoroughly heat it and thus assist in vaporizing the mixture passing through the intake pipe.

As an auxiliary or safety outlet a pipe connection 23 is provided from the upper part 110

2
of the jacket 17 of the left-hand conduit section 13 to the jacket 17 of the right-hand conduit section 13. Thus in case of an excess of water in the left-hand section some of it 5 will pass out at the top of the jacket and into the jacket of the right-hand section. The normal flow, however, will still be through the jacket 20 of the section 14.

While I have herein described in some detail a specific embodiment of my invention, which I deem to be new and advantageous and may specifically claim, I do not desire it to be understood that my invention is limited to the exact details of the construction, 15 as it will be apparent that changes may be made therein without departing from the spirit or scope of my invention.

Having thus described my invention, what I claim and desire to secure by Letters Patent is:

1. In a hydrocarbon motor the combination with the water jacketed cylinders, of a jacketed intake pipe formed by a lower and two upper sections, inlet means from the cylinder jackets to the jackets of the upper pipe sections, outlet means from the jacket of one of said upper sections, and communicating means between the jacket of the lower pipe section and each of the upper sections.
2. In a hydrocarbon motor the combination with the water jacketed cylinders, of a jacketed intake pipe formed by a lower and two upper sections, inlet means from the cylinder jackets to the jackets of the upper pipe sections, outlet means from the jacket of one only of said upper sections, and passages connecting the jacket of the lower section with the jackets of the upper sections.

3. In a hydrocarbon motor the combination with the water jacketed cylinders, of a 40 jacketed intake pipe formed by a lower and two upper sections, inlet means from the cylinder jackets to the jackets of the upper pipe sections, outlet means from the jacket of one only of said upper sections, and 45 passages connecting the jacket of the lower section with the jackets of the upper sections, and a passage connecting the jackets of the upper sections.

4. In a hydrocarbon motor, the combination with a series of water jacketed cylinders having jacket outlets near the tops, of a jacketed intake pipe formed of two sections connected to the cylinders, and a third jacketed section connected to the other two, water 55 inlet means from the top of the cylinders to the jackets of the cylinder connected sections, outlet means from the jacket of one of said two sections, and connections from the jacket of the third section to each of the 60 other two.

5. In a hydrocarbon motor, the combination with a series of water jacketed cylinders having jacket outlets near the tops, of a jacketed intake pipe formed of two sections connected to the cylinders, and a third jacketed section connected to the other two, water 65 inlet means from the top of the cylinders to the jackets of the cylinder connected sections, outlet means from the jacket of one only of said two sections, connections from the jacket of the third section to each of the 70 other two sections, and a pipe connecting the jackets of the said two sections.

In testimony whereof I affix my signature. 75
JESSE G. VINCENT.
